UNITED STATES PATENT OFFICE.

EMIL STAHELIN, OF CHICAGO, ILLINOIS, ASSIGNOR TO SHURLOX AWNING & SHADE COMPANY, OF CHICAGO, ILLINOIS, A CORPORATION OF ILLINOIS.

AWNING.

Application filed December 30, 1921. Serial No. 525,868.

This invention relates to improvements in awnings and particularly to those in which a portion of the fabric is held parallel to the window when the awning is in use, while another portion is held at an angle to the window. The United States Patent No. 1,250,239, granted to me Dec. 18, 1917, illustrates and describes an awning of this nature on which my present invention is an improvement. This patent discloses a ratchet rack fixed to the window-sill for adjusting the angle of elevation of the awning. One of the objects of my present invention is to obviate the necessity of connecting this rack to the window-sill so as to simplify the installation of the awning by making the framework substantially self-contained. Another object is to be able to more definitely and dependably operate the awning. Other objects of the invention will be apparent from a consideration of the accompanying drawings and the following description thereof.

Of the drawings Fig. 1 is a perspective view of an awning and the supporting frame thereof fixed to a window-sill, the awning and frame embodying the features of my invention; Fig. 2 is an enlarged side elevation of the lower portion of the awning and frame in the normal position; Fig. 3 is a side elevation of the same with the awning and frame elevated to the closed position so that the awning is substantially removed from the front of the window; Fig. 4 is an enlarged perspective view of a ratchet rack used to adjustably position the awning; and Fig. 5 is a materially enlarged sectional view along the line 5-5 of Fig. 2.

The awning, as shown by the drawings herein, is fixed to the window-sill 10 by means of a framework which is supported to the sill by brackets 11 and guide rods 12, one end of each of the rods being fixed to the sill, and the other end passing through openings in the lugs 13 of the bracket. Slidably and rotatably mounted on the rod 12 are members 14 and 15 connected by a link 38. All of these awning supporting means are duplicated on the two vertical sides of the

window-sill. A bar 16 is pivoted at its inner end to each of the members 15, and the outer ends of the bars 16 support a rod 17 to which the lower end of the awning fabric 18 is fixed. From the rod 17 the fabric 18 normally extends upwardly and towards the window and passes under a rod 19 fixed by the brackets 20 to the window-sill. The fabric then passes upwardly and is fixed to a roller-bar 21 which is pivoted, by means of brackets 22, to the window-sill. A reel 23 is fixed to and concentric with one end of the roller-bar 21; and an operating cord 24 is wound around the reel 23 a sufficient number of times; and then passes downwardly. The weight of the bars 16 and the awning 18 will tend to rotate the reel and wind up the cord, but if the cord is fixed by its lower end the awning will remain supported and may be thus maintained at any desired position. Any suitable means may be used for holding the lower end of the cord. I prefer to pass it around a pulley 25 supported by a bracket 26, and then to a cleat 37 about which the cord may be wrapped.

I also provide means for firmly holding each of the bars 16 against upward movement. Each of these means comprises a link 27 having one end pivoted to the member 14 and the other end having a pin 28 fixed thereto which is adapted to coact with the teeth 29 fixed to the bar 16. When the bars 16 are in the position shown by Figs. 1 and 2, it is obvious that the ends of the bars 16 cannot be revolved upwardly; hence, by pulling tightly on the cord 24, the awning will be stretched firmly in place, and the particular angle of the bar 16 will depend upon the particular notch 29 with which the pins 28 coact.

In order to suitably operate the bars 16 to adjust the position of the awning, or to remove it entirely from in front of the window, I provide means for removing the pins 28 out from coaction with the teeth 29, so that the outer ends of the bars 16 may be elevated. These means comprise a guard 30 pivoted at the point 31 to each of the arms, the guard extending over the teeth of the

arm. When it is desired to elevate the outer ends of the arms the cord 24 is released and the awning and the outer ends of the bars 16, by virtue of gravity, are lowered, and the pins 28 move inwardly on the bars 16. When the inner notch of the ratchet is reached the upper edges of each arm, coacting as a cam, cause the pin 28 to elevate the inner end of the guard 30 so that the pin 10 passes down onto the portion 32 (Fig. 2) of the arm 16. Then, as the arm 16 is turned upwardly, the pin 28 slides outwardly and passes onto, instead of beneath, the guard 30. As the outer end of the arm 16 is 15 revolved towards the vertical position the pin 28 will pass outwardly along the housing 30 until the recess 33, in the guard is reached, when the pin will drop into the depression 34 in the bar 16; and, as the bar is 20 turned still further, the pin will pass under the flange 35 of the guard. If properly designed, the arm 16 will then be nearly vertical, as indicated in Fig. 3, and the outer end of the arm 16 will have passed under 25 the stay rod 19. If the operator then continues to pull on the cord 24, the awning 18, being fixed to the upper ends of the bars 16, will pull these bars upwardly, with the members 14 and 15 sliding on the rods 12, 30 and this will continue until the lower end of the awning substantially reaches the roller-bar 21; and, hence, is substantially removed from in front of the window.

When it is desired to lower the awning to the normal position the cord 24 is released from the cleat 37 and the frame and awning will descend by virtue of the force of gravity until the members 15 come into contact with the brackets 11. The upper ends of the bars 16, when elevated, slant outwardly 35 slightly from the window-sill, as indicated in Fig. 3, as the pins 36, coming in contact with the links 38, prevent the bars 16 from reaching the vertical position. Hence, the 40 weight of the bars 16 will cause the outer ends to move downwardly and outwardly from the window. As this occurs, the flanges 35 will hold the pins 28 in the depressions 34, and, hence, the upper ends of 45 the links 27, will be turned downwardly also. The pins 28 will then continue to pass inwardly along the depression 34 and under the guard 30 and into coaction with the teeth 29, moving the guard 30 upwardly so 50 far as is necessary. In this manner the outer ends of the bars 16 may be allowed to move downwardly to any desired position, the ordinary position being that indicated in Fig. 2, and by pulling tightly and fastening the rope the awning will be held in the 55 position desired.

It will thus be seen that I have provided a substantially self-contained awning frame, which is easily installed; and one so arranged that the awning may be quickly and 60

conveniently lowered, and adjusted when desired, or raised substantially clear of the entire window.

I claim as my invention:

1. The combination of an awning fabric and its supports including a guide and an outwardly swinging arm, a brace pivotally connected to said guide and extending outwardly to said arm, holding means located on said arm with which the outer end of 75 said brace is normally engageable and from which it is disengaged by the lowering of the arm, and means mounted on said arm for preventing the engagement of said brace and said arm as said arm is being raised. 80

2. The combination of an awning fabric and its supports including a guide and an outwardly swinging arm, a brace pivotally connected to said guide and extending outwardly to said arm, holding means located on said arm with which the outer end of said 85 brace is normally engageable and from which it is disengaged by the lowering of the arm, means mounted on said arm for preventing the engagement of said brace and said arm 90 as said arm is being raised, and means for reengaging said brace and said arm when said arm has been raised to a predetermined position.

3. The combination with an awning fabric and its supports, including a guide and an outwardly swinging arm, of a brace pivotally connected to said guide, and a ratchet fixed to said arm with which the outer end of said brace engages when the 100 awning is lowered, and a movable guard adjacent the ratchet and adapted to be displaced by the brace upon the abnormal lowering of the awning, said brace escaping from the guard and adapted to travel upwardly along the outer side thereof when the awning is raised from its abnormal lowered position. 105

4. The combination of an awning fabric and its supports, including a guide and an outwardly swinging arm, of a brace pivoted 110 to said guide, a ratchet fixed to said arm with which said brace engages in the lowering of the awning, a movable guard adjacent the ratchet and beneath which the brace engages said ratchet and means associated with said arm for disengaging the brace from the ratchet and displacing the guard, said brace escaping from the guard and being adapted 115 to travel outwardly along the upper side thereof in the raising of the awning from the abnormal lowered position. 120

5. The combination of an awning fabric and its support, including a guide and an outwardly swinging arm, of a brace pivotally connected to said guide by one end and with its other end extending outwardly along said arm, a ratchet fixed to said arm with which said brace engages in the lowering 125 of the awning, a movable guard adjacent 130

the ratchet and beneath which the brace engages with the ratchet, and a cam associated with the ratchet and guard for disengaging the brace from the ratchet, and thereby displacing the guard, said brace escaping from the guard and being adapted to travel outwardly along the upper side thereof in the raising of the awning from its abnormal lowered position.

10 6. The combination with an awning fabric and its supports, including a guide and an outwardly swinging arm, of a brace having one end pivotally connected with said guide, and with its outer end extending adjacent said arm, a ratchet fixed to said arm with which said brace engages in the lowering of the awning, and a pivoted guard adjacent the ratchet and adapted to be displaced by the brace upon abnormal lowering 70 of the awning, said brace thus escaping from the guard and adapted to travel upwardly along the outer side thereof in the raising of the awning from its abnormal lowered position.

15 7. The combination with an awning fabric and its supports, including a guide and an outwardly swinging arm, of a brace pivotally connected with said guide, a ratchet fixed to said arm with which said brace engages in the lowering of the awning, a removable guard adjacent the ratchet and beneath which the brace engages, and means associated with the ratchet and guard for disengaging the brace from the ratchet and allowing said brace to escape from the guard and to travel outwardly along the upper surface thereof in the raising of the awning from its abnormal lowered position.

20 8. The combination with the awning fabric and its supports, including a guide and an outwardly swinging arm, of a brace pivotally associated with said guide by one end, a ratchet fixed to said arm with which the other end of said brace engages in the lowering of the awning, a movable guard adjacent the ratchet and beneath which the brace engages, and a cam associated with the ratchet and guard for disengaging the brace from the ratchet, and thereby swinging the guard upwardly, said brace escaping from the guard and adapted to travel outwardly along the upper side thereof in the raising of the awning from its abnormal lowered position.

25 9. The combination with the awning fabric and its supports, including a guide and an outwardly swinging arm, of a brace pivotally associated with said guide, by one end, a ratchet fixed to said arm, a pin fixed to the other end of said brace and normally coacting with said ratchet, a movable guard adjacent the ratchet and adapted to be displaced by said pin upon abnormal lowering of the awning, said pin escaping from the guard and adapted to travel outwardly 30 along the upper side thereof in the raising

of the awning from its abnormal lowered position.

10. The combination with the awning fabric and its supports, including a guide and an outwardly swinging arm, of a brace 70 having one end pivotally associated with said guide and with the other end extending outwardly along said arm, a ratchet fixed to said arm, said brace engaging with the ratchet in the lowering of the awning, and a guard adjacent the ratchet, the guard being pivoted to said arm by one end, and the other end of said guard being adapted to be displaced by the brace upon abnormal lowering of the awning, said brace escaping 80 from the guard and adapted to travel along the upper side thereof in the raising of the awning from its abnormal lowered position.

11. The combination with the awning fabric and its supports, including a guide and an outwardly swinging arm, of a brace having one end pivotally associated with said guide and with its free end extending along the upper side of said arm, a ratchet fixed to the upper side of said arm with 90 which the free end of the said brace engages in the lowering of the awning, a guard adjacent the ratchet with one end pivoted to said arm and with the other end resting on said arm, and said brace being 95 adjusted to move inwardly along said arm and between the edge thereof and said guard upon abnormal lowering of the arm and thus to escape from beneath said guard and to travel upwardly along the upper side in the raising of the awning from its abnormal lowered position.

12. The combination with the awning fabric and its supports, including a guide and an outwardly swinging arm, of a brace 105 pivotally connected with said guide by one end, and with its free end extending along the upper end of said arm and adapted to coat therewith, said brace and arm having other coacting parts which limit the upward swing of the arm when the awning is raised and keep it off a dead center.

13. The combination of an awning and supporting means therefor, with means for normally holding the lower end of said awning a material distance away from said supporting means, means normally coacting with said holding means to prevent upward movement of said holding means, and means mounted on said holding means for preventing the coaction of said two coacting means, when said holding means is lowered and then raised.

14. The combination of an awning and supporting means therefor, with means for normally holding the lower end of said awning a material distance away from said supporting means, means normally coacting with said holding means to prevent upward movement of said holding means, and means

for preventing the coaction of said two co-
acting means, when said holding means is
lowered and then raised; and other means
for bringing said normally coacting means
again into coaction after said holding means
is being lowered from its raised position.

15. In an awning support an outwardly
swinging arm, a brace pivoted to said sup-
port by its inner end and with its outer end

normally coacting with said arm, means for 10
revolving upwardly the outer ends of said
arm and brace until they are nearly verti-
cal, and means associated with said arm for
rotating said brace downwardly when said
arm is lowered.

15
In testimony whereof, I hereunto set my
hand.

EMIL STAHELIN.
